OF YOUNGSTOWN, OHIO, A CORPORATION OF OHIO.

DESIGN FOR A WHEEL-TIRE.

No. 39,575.

Specification for Design.

Patented Sept. 22, 1908.

Application filed May 25, 1908. Serial No. 435,006. Term of patent 14 years.

To all whom it may concern:

Be it known that I, Tod J. Mell, a citizen of the United States, residing at Youngstown, in the county of Mahoning and State of Ohio, have invented a new, original, and ornamental Design for Wheel-Tires, of which the following is a specification, reference being had to the accompanying illustrations, forming part thereof.

In the accompanying drawings Figure 1 is an elevation or top plan view of the present design, and Fig. 2 represents the design in perspective.

This invention relates to a new, original, and ornamental design for wheel-tires in general, but is chiefly designed for the ornamentation of the outer cover or casing of automobile tires; and it consists, generally stated, in the shape and exterior configuration of the same, as will be hereinafter described and claimed.

The cross sectional area of the body 1 of the casing is of substantially circular form at all points throughout its circumference and in this particular does not materially differ from other casings. The exterior or tread-surface 2, however, as shown by the accom-

panying illustration, is ornamented and configured by a symmetrical arrangement of protuberances or elongated studs 3, of uniform length, width and thickness which encircle the entire structure and are arranged in parallel rows, those of each row being staggered to break joints with those of the row next adjacent as shown. As a consequence of such arrangement it will be noted that a line drawn transversely across the present tire will intersect opposite ends of one stud 3 of each successive row, and a right line similarly drawn through corresponding ends, or any corresponding point, of the studs 3 in each successive row will cross the tire diagonally; while a line intersecting one stud of each row centrally, crosses the structure in a zigzag manner, thus producing an effect most pleasant to the eye, as represented by the accompanying illustration.

I claim—

The ornamental design for a wheel-tire as shown and described.

TOD J. MELL.
